Patented Feb. 1, 1910.

UNITED STATES PATENT OFFICE.

CHARLES TELLIER, OF PARIS, FRANCE.

MACHINERY FOR PRODUCING MOTIVE POWER.

947,867.

Specification of Letters Patent.

Patented Feb. 1, 1910.

Application filed May 25, 1905. Serial No. 262,290.

To all whom it may concern:

Be it known that I, CHARLES TELLIER, a citizen of the Republic of France, residing in Paris, France, have invented certain new and useful Improvements in Machinery for Producing Motive Power, of which the following is a specification.

This invention relates to machinery for the production of motive power based on the employment of air compressed isothermically and superheated, by the combustion of fuel either directly or indirectly. I will describe the same with reference to the accompanying drawing which shows a vertical section of an apparatus in which solid fuel or non-volatile combustible liquids are employed.

The apparatus shown in the drawing is assumed to be applied to the raising of water; it may, however, be equally well applied to other purposes for which motive power is required. The object of this particular construction is to show that it can be worked automatically without requiring to be supplied with fuel except at long intervals of time, such as twelve hours or longer.

The following are the principal devices of the construction. *a* is the motor cylinder, *b* is an air compressing pump, *c* the water pump, *d* a group of re-heating tubes, *e* the heating tubes, *f* the combustion chamber, *g* the fuel-feeding device, *h* a steam coil.

The motor cylinder *a* can be worked with any known system of slide or other valves, either arranged for variable expansion or not. The motor cylinder *a* arranged as described, receives compressed and superheated air by means which I will proceed to describe. The pump *b* operating with isothermal compression, which has to supply the compressed air, is composed of two spaces *o p* which may be either cylindrical or rectangular and which communicate with a cylindrical chamber *q* and an opening *r*. In the chamber *q* is a piston *s* which is actuated by the motor cylinder *a* by means of twin connecting rods connected to the head *t* of a slide by means of a pivotal connection at *u*, the one connecting rod is shown at *v v* passing behind the piston rod, and the compression pump, being connected at *w* with the junction piece *x*, which connects the piston rod *y* of the pump *b* with the piston rod *z* of the water pump. Any other arrangement for establishing the said connection may be employed. The pistons of the cylin-

ders *a* and *b* can be connected by means of a crank shaft.

A fly wheel is mounted on the motor shaft 1^a, as indicated in dotted lines at 1, for 60 equalizing the motion. Pulleys or other transmission devices can also be fixed on the same motor shaft which can thus be made to distribute the motive power in any desired manner, such motive power being applicable to a great variety of purposes.

Referring to the compression pump *b*, the chambers *o p* are filled with perforated metal plates 2 2 situated at from 3 to 4 mm. apart, suitable distance pieces such as rivets 70 being provided on the plates for maintaining them apart; during the suction period of the pump, water enters the chambers *o* and *p* through the passages 3 and 4. During the pressure stroke this water, which fills 75 the whole pump with the exception of the air chamber formed by the displacement of the piston *s*, is forced, together with the compressed air, through the discharge valves; each of these discharge valves is 80 arranged together with an air suction valve, on the one hand in the box 5 of the chamber *o*, and on the other hand in a box indicated at 6 of the chamber *p*. These valves may be of any known construction. 85

The water supplied to the pump, under a slight pressure, is introduced during the suction period through the channels 3 and 4, at the same time that air is drawn in through the suction valves at 5 and 6; each 90 of the water channels is provided with a check valve, that for 4 being shown at 7; a cock 8 is provided on the supply pipe for regulating the supply. If no head of water for the supply is available it is forced in 95 by means of a small pump driven by the motor.

The advantages afforded by the above described compression pump are as follows:—

1. By means of the perforated metal plates 2, 2, which at each stroke of the pump have the water current passing through them, the entire heat of the air compression is absorbed by the water and carried to the outside.

2. There are no dead spaces as all the spaces of the pump are filled by the water passing through.

3. No escape of water through the stuffing box is possible as this is also covered by water, which is also the case with the valves.

4. The chambers *o p* can be made of any

desired size, the larger the capacity the slower will be speed of the water and the freer will be the passage for the air. The air compressed by the pump *b* issues by the 5 pipe *9* and through a similar pipe *9^a* below. This air being mixed with water is conveyed into an automatic separator arranged behind the apparatus, and therefore not shown. It may be of any known construction and need 10 not be further described. The water discharged from the same being under a certain pressure, can be utilized in any suitable mechanism.

The air escaping from the separator 15 passes through a pipe *10* shown at the top of the apparatus with bend *11* into the annular heating space *12*. A plate *13* placed under the inlet for the air facilitates the uniform distribution thereof to all the heating 20 tubes. Into the annular space *12* open the upper ends of the inner tubes *14* which pass down to near the closed lower ends of the outer tubes *15* which are heated externally as will be presently described; the 25 compressed air consequently passes from the chamber *12* down the tubes *14* and issues thence into the annular space between these and the tubes *15* in rising through which it comes into intimate contact with the heated 30 walls of *15*. From the upper ends of the tubes *15* the air passes into a second annular space *16* with which communicate several channels *17* leading the compressed air into the central upper chamber *18*. Into 35 this chamber open other tubes *19* passing down to the closed lower ends of the outer tubes *20*, which are heated externally directly by the fire heat, so that the air passing up through the same becomes super- 40 heated to the required extent and issues into the central chamber *21* whence it passes through the opening *22* and pipe *23* to the admission valve *24* by means of which it is admitted to the motor cylinder *a*. After 45 performing work in the motor cylinder the expanded air issues through a pipe *28*, preferably having a part formed in elastic material such as caoutchouc, that will yield to a certain extent to the pulsations of the es- 50 caping air so as to prevent concussions as the air escapes with some pressure.

The pipe *28*, as indicated in dotted lines, is provided with several branches *29* through which the expanded air enters the 55 narrow annular space *30*. The air descends in this space and issues at the bottom thereof into a conduit *31*, which leads it into the space *32* of the furnace. From this space it passes up through the grate *33* into the 60 combustion chamber charged with fuel. The hot gases resulting from the combustion pass upward through an opening *d'* into the central space surrounding the group of tubes *d*, and inclosed by a cylindrical 65 wall *34* formed of two concentric sheet iron

cylinders *35*, *36*, the annular space between which is filled with ashes or other bad conductor of heat. Or the cylindrical wall might be constructed of fire clay. Thus the hot combustion gases in rising up between the tubes *20* impart a great portion of their heat thereto and after issuing at top into the narrow space *37*, they again descend through the annular space in which are situated the tubes *e* to which they impart a further portion of their heat. At the lower end of the said annular chamber the combustion gases pass into a passage *38*, from which they pass into the narrow annular space *39*, communicating at the upper 70 end with a chimney flue *40*, through which they escape into the open air. If necessary a further quantity of heat might be taken up from the combustion gases by arranging in the chimney, or otherwise, a suitable 75 counter current apparatus, of known arrangement, for imparting heat to a fresh supply of air.

The fuel supply for the furnace is contained in a chamber *g* which is filled therewith through a movable plate *41*, the feeding piston *42* of this chamber being at that time drawn back by means of the screw spindle *43*, the backward turning of which is facilitated by releasing a locking device 90 *44*, which locks it to the piston *42*, so that it is then free to be turned by means of the crank handle *45*. The chamber *g*, having been filled with fuel, the screw spindle *43* is again locked to the piston so as to be prevented from rotating, and the plate *41* is again secured in position by means of screw nuts *46*. For feeding the fuel into the furnace the screw spindle, and with it the piston are advanced very slowly by means of a 95 screw sleeve mounted thereon which is rotated by means of a worm wheel *47* fixed thereon, which is engaged with a worm on a shaft *48* rotated by a worm wheel *49* and a worm *50*, mounted on a shaft *51* receiving 100 rotary motion by means of a worm wheel *52* gearing with a worm *53* which receives motion from the driving shaft in any suitable way. The forward motion of the screw spindle is so regulated by the above described gear that the fuel falls continuously 105 in very small quantities into the combustion chamber so as to be very effectually burned without producing smoke. In place of the above described feeding gear any 110 other suitable automatic feed apparatus such as a revolving feed worm may be employed.

The fire grate is constructed of a fixed part consisting of the bars *54* and a movable 115 part consisting of bars *55* combined with a transverse bar *56* which can slide in guides *57*. A shaft *58* extending below the bar *56* carries at its outer end a chain wheel *59* geared by a chain *60* with a chain wheel *61* 120

fixed to the before mentioned screwed sleeve of the spindle 43, so as to be rotated thereby and thus impart a slow rotation, such as two or three revolutions per hour, to the 5 shaft 58. This has a tappet 62 which at each revolution comes in contact with a projection 63 on the bar 56 and lifts this together with the grate bars 55, and then allows them to drop again. By this motion of 10 the grate bars the cinders and clinkers are broken up, and made to fall through the grate into the ashpit 64, whence they are removed through a suitable door near the bottom. The door 65 is for removing stones or 15 clinkers from the furnace.

Over the combustion chamber is arranged a coil *h* which is supplied by a small pump 66 through a pipe 68 with a very small quantity of water drawn by a pipe 67 from 20 a suitable tank. The rod of the pump 66 is connected by an arm 69 to the connecting sleeve *x* of the piston rods *y* and *z*; it could, however, be worked otherwise, such as by an eccentric on the motor shaft. The water 25 forced into the coil *h* is converted into steam which passes through pipe 70 and through an external pipe connected therewith into the before mentioned upper space 18 of the heating apparatus which it enters through 30 the opening 71, and in which it mixes with the compressed heated air and in passing with the same through the tubes 20 becomes superheated and co-operates with the air in the motor cylinder. This steam will become 35 condensed during the expansion of the air, and will impart its heat to the latter so that its expansion will take place approximately isothermically.

The pump *c* for raising water may be of 40 any suitable known construction; it may be replaced by an air compressing pump serving to raise water by compressed air in the known manner.

The starting of the apparatus may be facilitated by means of a chamber 72 having a 45 cock at each end, into which water is introduced and whence it is allowed to descend

into the heating apparatus by opening the lower cock, so that by being there converted into steam and then passing to the motor 50 cylinder, it suffices to start the apparatus. A safety valve is provided at 73.

When setting light to the fuel in the combustion chamber the valve 74 closing the chamber below the grate is opened. As, 55 however, it requires to be closed during the working, its axis carries a chain wheel connected by a chain 75 to a chain wheel on the axis of the starting valve 24, so that on opening this for starting the motor, the closing of valve 74 is automatically effected. 60

It will be readily understood that the details of the apparatus above described can be variously modified without departing from the nature of my invention. 65

I claim as my invention:—

An apparatus of the class described, including a heater having a furnace with a cylindrical body arranged above it, said cylindrical body containing an annular space 70 and a central space, a cylindrical refractory wall separating said spaces, and a series of tubes depending in said spaces, a cover from which said tubes depend and containing compartments with which said series of 75 tubes communicate at their upper ends, a second series of tubes into which the first series plunge and which are closed at their lower end and open at their upper end into other compartments arranged in said cover, 80 and connections between said compartments such that the cold air comes into contact with the furnace gases which are least hot, and the air already partly heated comes into contact with the furnace gases which are 85 hottest, so that the air may be highly heated with constant volume.

In witness whereof I have hereunto signed my name this 11th day of May 1905, in the presence of two subscribing witnesses.

CHARLES TELLIER.
